UNITED STATES PATENT OFFICE.

JOSEPH GOLDSMITH, JR., OF CHICAGO, ILLINOIS.

HAIR-CURLING DEVICE.

Application filed December 1, 1921. Serial No. 519,034.

To all whom it may concern:

Be it known that I, JOSEPH GOLDSMITH, Jr., a citizen of the United States, and resident of the city of Chicago, county of Cook, 5 and State of Illinois, have invented a certain new and useful Improvement in Hair-Curling Devices, of which the following is a specification.

This invention relates to a hair curling 10 or crimping device and has for its object to provide a device of this character which receives and retains the hair and aids in producing a curled or waved appearance of the same.

15 This object is attained by means of my device which consists generally of a strip of flat resilient material bent upon itself to form a pair of opposing arms which receive, grip, press and crimp the hair between them, a strand of hair being usually spirally wound on one of the arms.

A further object of my invention is to provide a device of this character in which the two arms are provided with interengaging 25 means which lock them together so that they cannot inadvertently separate while the device is in use and particularly when a large amount of hair is wound on one of the arms.

30 With these objects, and other objects which may hereinafter appear, in view, I have devised the particular arrangement of parts hereinafter set forth and more particularly pointed out in the claims appended 35 hereto.

Reference is to be had to the accompanying drawing forming a part hereof in which—

Figure 1 is a plan view of my improved 40 hair curling device in its closed position.

Figure 2 is a side elevation of the same.

Figure 3 is a plan view of one end of the hair curling device showing the locking means for holding the two ends of the arms 45 together.

Figure 4 is a sectional view on the line 4—4 of Figure 3 looking in the direction of the arrows.

Figure 5 is a perspective view of the end 50 or tip of one of the arms showing its rounded formation.

Figure 6 is a sectional view on the line 6—6 of Figure 5 looking in the direction of the arrows.

55 Figure 7 is a sectional view on the line

7—7 of Figure 3 looking in the direction of the arrows, and

Figure 8 is a perspective view of the end of the arm provided with the locking loop.

Throughout the various views of the 60 drawings, similar reference characters designate similar parts.

In the preferred embodiment of my invention as disclosed in the accompanying drawing, the hair curling device is preferably constructed of a continuous strip of flat resilient material transversely folded upon itself to form a loop 1, and a pair of oppositely disposed, normally separated, 65 spring arms 2 and 3. The arm 2 is provided at its end with a tapered portion bringing the end down to a point and said end is arched or transversely curved as at 4.

The other arm 3 has its end curled or 70 rolled up to form a loop portion 5 which acts as a guard member for the end of the arm 2 and also acts as a locking member therefor. The end of the loop portion 5 is provided with a recess or notch 6 within 75 which the end or tip 7 of the arm 4 is adapted to lie when the device is in its locked position. The end of the looped portion 5 is provided with projections 7 and 8, the projections 7 being formed on 80 each side of the recess 6 and the projection 8, which is shorter than the projection 7, lies within the recess.

It will be seen that the transversely round or curved tip 4 on the arm 2 fits within the 85 recess 6 and conforms to the curve thereof. The arm 2 is provided in its tip 4 with an aperture 9 adapted to be engaged by the projection 8 in the recess.

Lateral or sideways movement of the arm 90 2 is prevented by the notch 6 and the projection 8 entering into the aperture 9 prevents the arms 2 and 3 from separating when a large amount of hair is wound upon the arm 2.

100 In using my improved hair curling device, a strand of hair is wound spirally about the arm 2 and the arms 2 and 3 are pressed together and the arm 2 is moved from one side and brought to rest under 105 the looped guard 5. The normal tendency of the arms 2 and 3 to spring apart causes the aperture 9 in the arm 2 to snap into engagement with the central projection 8 on the guard. Should there be a tendency of 110

the arm 2 to move out of engagement with the projection 8 during the use of the device, it will snap into engagement with one or the other of the side projections 7 so that an inadvertent separation of the arms during the use of the device is very unlikely.

From the foregoing it is obvious that my invention is not to be limited to the exact embodiment shown, but is broad enough to 10 cover all structures coming within the scope of the annexed claims.

What I claim is:—

1. An article of the class described comprising a hair curler having a pair of arms, 15 one of said arms terminating in a rounded loop in which a recess is formed to receive the other arm, a projection formed within said recess, which projection is adapted to lie within an aperture formed in the arm 20 which has its end lying within the recess in the loop.

2. An article of the class described comprising a hair curler having a pair of arms, one of said arms terminating in a rounded 25 loop, said loop being provided with a recess confined between a pair of projections, a central projection situated between the first-mentioned pair of projections, with the other arm having an end adapted to lie 30 within the pair of projections and having

an aperture adapted to receive the central projection.

3. An article of the class described comprising a hair curler having a pair of arms, a loop formed on the end of one of said arms, said loop being provided with a recess and a projection in said recess, and the other arm being provided with an aperture in its end adapted to be engaged by said projection.

4. An article of the class described, comprising a hair curler having a pair of arms, one of said arms terminating in a rounded loop provided with a recess, a projection within said recess, the other arm having an 45 aperture adapted to receive said projection and having that portion wherein the aperture is located transversely arched.

5. An article of the class described comprising a hair curler having a pair of arms, a rounded loop formed on one of said arms, a recess formed in said loop, a transversely arched tip on the end of the other arm, a projection centrally located in the recess and adapted to enter into an aperture provided 55 in the arched tip of the arm.

Signed at the city of Chicago, Cook County and State of Illinois, this 29 day of Nov., 1921.

J. GOLDSMITH, JR.
